UNITED STATES PATENT OFFICE

ALFRED NEWLANDER, OF MILWAUKEE, WISCONSIN, ASSIGNOR, BY MESNE ASSIGNMENTS, TO E. J. BRACH & SONS, OF CHICAGO, ILLINOIS, A CORPORATION OF ILLINOIS

DISPLAY DEVICE

Application filed November 22, 1926. Serial No. 149,880.

This invention relates to display device and container for material to be both displayed and stored. The display device is of the type adapted to form a unit container. 5 These units are adapted to be arranged closely adjacent each other so as to display and store different material, each kind being placed in an individual unit.

The invention has for its object the production of unit containers which are adapted to display material on sale either by the placing of the unit containers themselves on a table or by placing them within a show case. Another object of the invention is to so construct a display device that the material can be readily removed from the device for the purposes of cleaning the device or changing the material to be displayed. Another object of the device is to provide a rear door therefor 20 which is easily detachable therefrom and also which is provided with weight means to hold the door either closed or open.

The invention is illustrated in the accompanying drawing forming part of this specification, in which Fig. 1 is a front elevation of a cabinet having nine of the display units, the subject of this invention, assembled therein.

Fig. 2 is a sectional view of the same.

30 Fig. 3 is an end view, partly in section, of the display device.

Fig. 4 is a longitudinal vertical section of the same showing material in place.

Fig. 5 is a horizontal sectional detail taken 25 on the line V—V of Fig. 6.

Fig. 6 is a longitudinal vertical section of a modified display device having a vertical front, the rear door being omitted.

Fig. 7 is a vertical sectional detail of the 40 upper part of the display device, mainly showing the transparent cover for the same.

Fig. 8 is a vertical sectional detail of the rear portion of the display device, showing the rear door and its mounting, and the de- 45 humidifier attached thereto.

The various figures are not to scale.

This invention is an improvement over the device disclosed in U. S. Patent 1,582,703 granted April 27, 1926, in the name of Stry- 50 ker, and while the general purpose of the in-

vention is substantially the same as that of this patent, namely, to simulate a full supply of material on hand and for sale while not necessarily having a full supply on hand in the storage part of the display device, yet 55 the present invention shows many advantages and improvements not disclosed therein.

The display device is made up of suitable material, preferably sheet metal and comprises sides 1, 2, a top 3, a bottom 4, and a front 5. The top 3 and the front 5 are depressed from the top and front edges of the device so as to form a top recess 6, a front recess 7 and a storage chamber 70.

Along the front side edges of the device are 65 formed guides 8, 9, within which a front transparent cover 10 is slideable. This transparent cover 10 slides within the guides 8, 9 and in its normal position has its lower edge located behind a lip 11 formed on the device. Rear lips 12 and 13 are respectively formed at the rear of the top 3 and bottom 4. A transparent top cover 14 is formed of a glass plate which has its edges protected by a metal frame 15 and sometimes open at the 70 rear (see Fig. 6) and which has depending flanges 16 along its side edges spaced apart sufficiently to easily take within the sides 1, 2 of the device. The front edge of the top cover 14 lies in contact with the top edge of 75 the transparent cover 10 so as to exclude dust from the device.

A clip 17 has a door 18 mounted thereon by means of spring hinges 19 tending to 80 close the door when the clip and door are mounted in place on the rear lip 13 on the bottom 4 of the device. On the door 18 is fixed a weight means or dehumidifier 20. This dehumidifier comprises a chamber container for deliquescent material which 85 removes moisture from the air within the main storage chamber 70 of the device. The weight means 20 is so located with reference to the hinge axis that its center of gravity is 90 respectively forward or rearward when the door is closed or open so that it will then tend to 95 remain in those positions.

The detail shown in Fig. 7 is a modification of the frame portion of the top cover 100

14, the depending flanges 16 in this case being bent back upon themselves for strength.

The modification shown in Figs. 5 and 6 is merely that of a device having a straight front instead of an inclined front.

5 It will be seen that when the front cover of the device is in place, material may be filled in the front recess 7 between the front cover and the front 5 and also in the top recess 10 6 after which the top cover 14 may be put in place. The storage part of the device may then be filled with a supply of material from which material sold may be taken from time to time. This material is readily accessible 15 through the rear door which when open will stay open and which when closed will stay closed, by reason of the weight means comprising a dehumidifier 20.

It will also be clearly seen that when a unit 20 is to be removed it can be slid back without disturbing adjacent units, the top cover 14 then removed and the front cover 10 slid upwardly a short distance so as to allow all the material in the front recess 7 and the 25 top recess 6 to flow out of the opening produced by raising the front cover this slight amount. Any material remaining in the storage chamber 70 can of course be poured out through the rear opening.

30 It will be clearly seen from Figs. 1 and 2 that this display device may be grouped in a series of units arranged closely side by side and will appear to a purchaser to show a full supply of material on hand when as a matter 35 of fact there may not be very much material in the storage chamber of the display device. It will also be clear that the cabinet shown in Figs. 1 and 2 may be in the form of a glass showcase or it may be merely a skeleton cabinet, the units themselves being entirely closed in to keep the material displayed in good condition in spite of dust and dirt in the surrounding atmosphere. It will also be clear that these units may be arranged in a 40 closed form of showcase.

45 It is claimed and desired to secure by Letters Patent:

In a display device, a unit container having an opening at the rear, a lip extending upwardly and rearwardly along the bottom edge of said opening, a clip for friction fastening to said lip and a door hinged to said clip.

50 In testimony whereof, the signature of the inventor is affixed hereto.

ALFRED NEWLANDER.
